UNITED STATES PATENT OFFICE.

ALEXIS BRETONNEAU, FILS, OF MORTAGNE-SUR-SEVRE, FRANCE.

IMPROVEMENT IN EXPANSION-VALVES FOR STEAM-ENGINES.

Specification forming part of Letters Patent No. 222,376, dated December 9, 1879; application filed October 11, 1879.

To all whom it may concern:

Be it known that I, ALEXIS BRETONNEAU, fils, of Mortagne-sur-Sevre, have invented Improvements in Expansion-Valves for Steam-Engines; and I do hereby declare that the following is a full, clear, and exact description of the same, reference being had to the annexed sheet of drawings, making a part of the same.

This invention relates to an improved system of variable expansion-valve for steam-engines, and is illustrated in the accompanying drawings.

Figure 1 is a vertical section of a steam-chest embodying my improved expansion-valve. Fig. 2 is a horizontal section of the steam-chest. Fig. 3 is a plan view of plate B. Fig. 4 is a diagram, showing the crank or eccentric K.

The invention consists of an expansion slide-valve, A, Figs. 1 and 2, on the back of the main slide-valve D, and of two movable cut-off plates, C C', on the back of the expansion-valve A, which do not participate in the motion of the slide-valve, but may be adjusted nearer or farther apart from one another by means of studs g g, each engaging in a curved slot in a plate, B, (shown separately in Fig. 3,) on turning which the slides C C' are moved toward or away from one another, in order to cut off earlier or later, and so vary the grade of expansion. A spring, y, presses lightly on the back of the plates C C', to keep them close against the expansion-valve A, and the latter against the main slide D.

The expansion-valve A is actuated by a crank or eccentric, placed at K, Fig. 4, diametrically opposite the driving-crank of the engine, if the latter runs both ways, or at K', a little in advance of this position, if it runs one way only, in order that the expansion-valve A shall be moving at a certain velocity when the cylinder-ports are uncovered by the main valve, and shall not arrive at the end of its travel until after the closing of the said ports, in order to avoid wire-drawing by the plates C C' at the beginning and end of the stroke. The two slide-valves D and A move independently, and the travel of the valve A depends on the space available in each case. Thus, in the example shown, the valve-chest being short and narrow, the travel of the slide A is only one-tenth of that of the main valve

D, and notwithstanding this, there is no wire-drawing of the steam. The ports of the main valve are also made wider at 1 and 2, in order that here, also, there shall be no wire-drawing. The dotted lines x show how the size of the port and the length of the valve would be increased for a more extended travel of valve A.

The plate B is fixed on a steel spindle, t, of the smallest possible diameter, passing through a stuffing-box in the cover of the valve-chest, and is operated by a governor or hand-lever. In order to set out the slots in plate B for the studs g, I mark on the line a a', Fig. 3, beginning at a point, 1, a little below line m m', the positions of the plate C, which correspond at the cut-off to one of the regular points of division of the piston-stroke (tenths, for instance) by the points 1, 2, 3, &c., and from these points, with o as a center, I describe arcs whose intersection with the radii o', o², o³, &c., give the center line of the curve for the slot which is to operate the plate C. For the other slot I proceed in the same way for the divisions of the line n n'; but instead of radii I draw tangents n' n² n³, &c., to lines which, like a a', each pass through a point of the first curve and tangentially to a circle, o o', described with the radius o a'. This gives two curves differing in proportion to the varying effect upon the piston due to the length of the connecting-rod and of the eccentric-rod of a valve.

The operation is as follows: When the piston is at the commencement of its stroke and the crank is at H, Fig. 4, the crank or eccentric operating valve A is at K', and the edge 4 of the port z is in line with the axis of plate B, so that if the plates C C' were brought quite close together the port z would not be uncovered at all, so that steam would not be admitted to the main valve, and the cut-off would then be at the very beginning of the stroke. Supposing the plates C C' to be separated each for the distance y', Fig. 4, corresponding to the travel of the expansion-valve A during the uncovering of the cylinder-port by the main valve, the expansion-valve A would have to move this distance y' before the edge 4 of port z would close the port, which would take place at the moment when the main valve closes the cylinder-port, and the cut-off will then be at the end of

the stroke of the main valve, supposing it to be without lap. The intermediate position of the plates C C' correspond to grades of expansion between these two extremes.

The apparatus is easily controlled directly by a governor, the power required to turn plate B being very small. It works without shock, there being no stop, and is consequently applicable to engines running at high speeds as well as engines running both ways. By placing the eccentric or crank which operates the expansion-valve A diametrically opposite to the driving-crank, this expansion-valve is in position for rotation either way of the crank-shaft, and it is only necessary to operate the main valve in order to reverse the engine, the expansion-valve being left to the control of the governor, if one be employed, whereby the elastic force of the steam is utilized to the greatest possible extent. The governor holding the plates C at their greatest distance apart when the engine is stopped enables it to be started again in either direction with full pressure, whereby irregularities and difficulties are avoided at the moment of starting, and the engine can be worked as if it had an ordinary D-valve, which are very important advantages.

I am aware that slide-valves have already been combined with expansion-valves, covers thereto, and slotted regulating-plates. This I do not claim; but in all previous arrangements the slots in the regulating-plates were either alike, which is a serious error, or constructed so as to give an equal movement to the two plates.

I claim—

The combination of the slide-valve D and sliding expansion-valve A with the plates C C', pins g g, spring y, slotted plate B, which has two curved slots of different form, said slots being formed, the one on radii o', o'', &c., the other on tangential lines n' n'', &c., so that by the motion of the plate B the position of the plates C C' is varied in proportion to the varying effect upon the piston due to the length of the connecting-rod and of the eccentric-rod of a valve, as and for the purpose set forth.

ALEXIS BRETONNEAU, FILS.
